D. PEVNY

WEDDING RING

Filed March 8, 1927

INVENTOR.

David Pevny

BY

R. L. Smith

ATTORNEY.

UNITED STATES PATENT OFFICE.

DAVID PEVNY, OF LOS ANGELES, CALIFORNIA.

DESIGN FOR A WEDDING RING.

Application filed March 8, 1927. Serial No. 21,060. Term of patent $3\frac{1}{2}$ years.

To all whom it may concern:

Be it known that I, DAVID PEVNY, a citizen of the United States, and resident of Los Angeles, county of Los Angeles, State of California, have invented a new, original, and ornamental Design for Wedding Rings, of which the following is a specification, reference being had to the accompanying drawing, forming part hereof.

The figure is a perspective view of a wedding ring, showing my new design.

I claim:

The ornamental design for a wedding ring as shown.

DAVID PEVNY.
